POWER SAW

Fred G. Carnes and Wilfred D. Carnes,
Au Sable Forks, N. Y.

Application January 30, 1945, Serial No. 575,259.

3 Claims. (Cl. 125—16)

This invention relates to a power saw, and more particularly to such a saw adapted to be used for the sawing of stones, as by stone masons or the like.

A primary object of this invention is the provision of an improved power saw characterized by means whereby the blade thereof may be moved in a linear direction, the blade being secured to supporting members at both ends.

An additional object of the invention is the provision of such a saw mounted on a frame, and having means in association therewith whereby the same may be readily raised and lowered as desired.

A further important object of the invention is the provision of means in association with the last-mentioned means for moving the saw blade, which simultaneously moves the drive mechanism for said saw blade, upwardly and downwardly in accordance with the movement of the blade.

An additional important object is the provision of an improved mechanical movement, whereby rotary motion of the drive mechanism is transmitted to reciprocating movement of the blade, and means for suitably supporting the blade in such manner as to permit such reciprocatory motion.

Still other objects reside in the provision of such saw which will be sturdy and durable in construction, reliable and efficient in operation, and relatively simple and inexpensive to manufacture and assemble.

Other objects reside in the combinations of elements, arrangements of parts, and features of construction, all as will be more fully pointed out hereinafter and shown in the accompanying drawings, wherein there is disclosed a preferred embodiment of this inventive concept.

In the drawings—

Figure 1 is a top plan view of one form of device embodying features of the instant invention.

Figure 2 is an end elevational view of the device shown in Figure 1.

Figure 3 is an enlarged sectional view taken substantially along the line 3—3 of Figure 2 as viewed in the direction indicated by the arrows, and

Figure 4 is an enlarged sectional view taken substantially along the line 4—4 of Figure 2 as viewed in the direction indicated by the arrows.

Similar reference characters refer to similar parts throughout the several views of the drawings.

Having reference now to the drawings, there is generally indicated at 10 a frame, comprised of upright corner posts 11, each having inwardly turned flanges 12, adapted to form vertically extending interiorly disposed channels. The corner posts 11 are connected by transverse horizontal members 13, serving as reinforcements, and holding the frame in assembled relation. Extending from the base of one pair of posts 11 are a pair of angled members 14, forming a triangular extension to the frame, and secured to the corresponding extremities of the horizontal members 13 is a second pair of angled members 15, vertically aligned with the members 14. Secured between the members 15 is a transverse supporting plate 16, adapted to carry an electric motor 17 provided with a drive pulley 18.

The motor 17 is adapted to drive, through a belt 20, a pulley 21 mounted on the extremity of a vertically extending shaft 22, mounted for rotation in suitable journals 23 carried by the members 14 and 15. A vertically extending groove 24 extends the full length of the drive shaft 22 between journals 23.

Mounted in aligned relation with the drive shaft 22 is a supporting rod 25, which has positioned for vertical movement thereon a pair of brackets 26, which, in turn, carry a gear supporting frame 27, within which is positioned a bevel gear 28, mounted on the shaft 22, and having an interiorly positioned key therein to key the same in the groove 24 in such manner that rotation of the shaft 22 is imparted to the gear 28. Bevel gear 28 engages a second bevel gear 29, also carried by the frame 27, and provided with a stub axle 30, to the extremity of which is secured a crank arm 31. The crank arm 31 is pivotally secured as by means of a pivot 32 to an extremity of a link 33, terminating in a transverse bracket member 34, provided at its extremities with collars 35, adapted to surround a pair of aligned oppositely disposed axles 36, carried by the frame in a manner to be hereinafter described.

As best shown in Figure 3, each of the axles 36 is journaled for rotation in a collar 37 carried by a horizontally positioned link 38, to the extremities of which are pivotally secured as by pivots 39 the extremities of additional links 40, the opposite extremities of which, in turn, are pivotally mounted as on pivots 41 in opposite corners of blocks 42. Each of the blocks 42 is mounted in the channel formed by the flanges 12 of the members 11, in such manner as to be vertically movable therein when moved, in a manner to be described hereinafter, but precluded

from horizontal movement by the side walls of the channel.

As best shown in Figure 1, the inner extremities of the axles 36 terminate in collars 43, in spaced relation, which collars are adapted to engage in any desired manner with the extremity of a stone cutting saw blade 44. The blade extends in a horizontal plane the full length of the frame, and has its opposite end secured between collars 43 carried by an additional pair of axles 36 substantially identical to the first-mentioned axles, and mounted in identical fashion on additional blocks 42.

From the foregoing it will now be seen that when the motor 17 is energized and drives through the shaft and gear arrangement above discussed, the crank 31 for rotary movement, that such movement is transmitted through the members 33 to reciprocatory movement of the axles 36, and that such reciprocatory movement is permitted in a horizontal plane by means of the links 38 and 40, and their pivotal relation with each other and with the blocks 42. It will also be seen that the axles 36 maintain their relative position in the same horizontal plane continuously throughout such reciprocatory motion, unless moved from an exterior source, in a vertical direction, in a manner to be more fully pointed out hereinafter.

Journalized in suitable upstanding lugs 50 on the upper extremities of frame members 13 are the extremities of a roller 51, adapted to be rotated by means of a hand wheel 52 carried by a shaft 53, carried by a lug 54 secured to the side of one of the longitudinal extending frame members 13, and terminating in a suitable worm gear adapted to engage a cooperating gear on the extremity of the shaft 51 (not shown) and contained in a gear box 55.

Suitable cords 56 surround the roller 51 at points adjacent each extremity, and extend over pulleys 57, rotatably mounted in suitable supporting brackets 58 at the upper extremities of each of the posts 11. The cords 56 extend to suitable eyes 59, secured in the top portion of each of the blocks 42. Additional cords 60 correspondingly surround the roller 51 and extend over pulleys 61, mounted on the interior surface of each of the posts 11. The cords 60 then extend downwardly over additional pulleys 62 mounted at the base of each of the posts 11, and thence upwardly to engage eyes 63 carried by the base of each of the blocks 42.

An additional cord 65 is coiled about the roller 51 at an intermediate point and extends over a pulley 66 carried by a supporting bracket 67, to an eye 68 carried by the upper extremity of the gear supporting frame 27.

Now from the foregoing it will be seen that when the hand wheel 52 is rotated, corresponding rotation of the rollers 51, acts through the cords or wires 56, 60, and 65, to move all of the blocks 42 either upwardly or downwardly in unison, in accordance with the direction of rotation of the hand wheel, and that simultaneously the

gear box frame is moved upwardly therewith, the weight of the device being sufficient to permit the same to move downwardly when the blocks 42 are moved downwardly, by gravity. Thus it will be seen that the saw blade 44 is maintained in a constant horizontal line, and at the same distance from the driving mechanism therefor at all times.

It will now be readily apparent that there is herein provided an improved power saw, adapted particularly for the use of stone masons or the like, accomplishing all the objects of this invention and others including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

We claim:

1. In a power saw, in combination, a frame, including uprights having channels therein, blocks vertically slidable in said channels, axles movably secured to said blocks, a saw blade carried for reciprocating movement by said axles, power means for reciprocating said blade, said means including a drive shaft and a gear frame slidably mounted on said shaft, means for simultaneously moving said blocks to vary the vertical position of said blade, and means associated with said last-mentioned means for simultaneously varying the position of said gear frame.

2. In a power saw, in combination, a frame, including uprights having channels therein, blocks vertically slidable in said channels, axles movably secured to said blocks, a saw blade carried for reciprocating movement by said axles, power means for reciprocating said blade, and means for simultaneously moving all of said blocks to vary the vertical position of said blade, said means including a rotatable roller, pulleys at the upper and lower extremities of each of said uprights, and cords passed over said pulleys and secured to the upper and lower extremities of said blocks.

3. In a power saw, in combination, a frame including uprights having channels therein, blocks vertically slidable in said channels, each of said blocks having a pair of oppositely disposed normally parallel links pivotally secured thereto, and a second link pivotally secured between the free extremities of said first-mentioned links, axles rotatably secured to the centers of each of said second links, a saw blade carried for reciprocating movement by said axles, power means for reciprocating said blade, and means for simultaneously moving said blocks to vary the vertical position of said blade, said means including a rotatable roller, pulleys at the upper and lower extremities of each of said uprights, and cords passed over said pulleys and secured to the upper and lower extremities of said blocks.

FRED G. CARNES.

WILFRED D. CARNES.
